GARMENT PROTECTOR

Anton F. Dasinger, Sidney, Mont.

Application August 4, 1950, Serial No. 177,688

2 Claims. (Cl. 2—51)

1

The present invention relates to a garment protector, which is particularly useful for press-men in dry cleaning and pressing establishments.

An object of the present invention is to provide a garment protector especially useful for men to protect a leg of a pair of trousers.

Another object of the invention is to provide a garment protector or apron which will be readily attachable to and detachable from a leg portion of a pair of trousers when worn by a person.

A further object of the present invention is to provide a garment protector for a trousers leg which is simple in structure and easy to manufacture.

Other and further objects will appear upon reference to the accompanying drawing, in which:

which:

Figure 1 is a front elevational view of the garment protector of the present invention applied to a person's neck.

plied to a person; and Figure 2 is an enlarged front view of the garment protector of the present invention.

Referring more particularly to the drawing, wherein like reference numerals refer to like parts throughout, the garment protector 10 comprises a body 11 fabricated of flexible material, such as woven fabric, leather, plastic, and so forth, and includes a section C adapted to cover the front portion of a trousers leg adjacent to and below the crotch of a pair of trousers, and a supporting section A positioned above and secured to the section C adapted to cover the front portion of said trousers leg intermediate the waistband and the crotch of the trousers. Specifically, the body 11 has one of its corners provided with a cut-away D, the cut-away extending from one end 13 substantially midway of the sides 12 and 15 of the body 11 to and terminating in the adjacent side 15 substantially midway of the ends 13 and 13' of the body 11 and conforming to the crotch of a pair of trousers. The portion of the body 11 contiguous to the cut-away D forms the supporting section A. Positioned adjacent to the free end of section A is tie string 16, a portion thereof intermediate its ends, designated by 17, being secured to said free end of supporting section A.

On the side 15 of the body 11 adjacent the cut-away 13 is attached one end of strap 19, as at 20, the other end of the strap or tape 19 being provided with a clasped hook 21 which is detachably engageable with a ring 22 positioned adjacent the other side 12 of the body 11, and is secured thereto by means of a strap 23 secured to the body 11, as at 26.

If desired, the front face of the body 11 may be provided with a pocket 27. As shown in the drawing, the pocket 27 is positioned upon the front face of the supporting strip A, adjacent to and spaced from the free end thereof.

The use of the device will be apparent. The user ties the string 16 around the waist and secures the ends together in any suitable manner, as by a knot 18. The spring clasp 21 is threaded between the legs and around the back of the right leg in the present showing, so that tape 19 embraces the back of the leg and clasp 21 is secured to ring 22, thereby bringing curved edge portion 14 of the cut-away D of the garment protector into the crotch of the user to secure the garment protector snugly to the leg of the user.

It will thus be apparent that the present invention provides a garment protector or apron that effectively protects the upper leg portion of a pair of trousers, and it is especially useful for pressmen who use their left leg to operate the machine and frequently rub the upper part of the right leg into contact with the machine. It will be also apparent that access can be obtained to the usual fly 24 of a pair of trousers without removing the apron.

It will be obvious that the garment protector is useful for many other purposes, and may be made for the right or left leg, as desired, and modified in other ways within the spirit and scope of the present invention.

I claim:

1. A garment protector comprising a body fabricated of flexible material, said body including a first section adapted to cover a front portion of a trousers leg adjacent to and below the crotch of a pair of trousers, a supporting section positioned above and secured to said first section adapted to cover the front portion of said trousers leg intermediate the waistband and the crotch of said trousers, said body being provided with a cut-away extending from one end of said body substantially midway of the sides of said body and to and terminating in the adjacent one of the sides of said body substantially midway of the ends of said body and conforming to the crotch of a pair of trousers, the portion of the body contiguous to the cut-away forming said supporting section, a tie string positioned adjacent to the free end of the supporting section and having a portion thereof intermediate its ends secured to said free end, and fastening means on the sides of said first-named section for securing the garment protector about the leg of the user.

2. A garment protector comprising a body fabricated of flexible material, said body including a first section adapted to cover a front portion of a trousers leg adjacent to and below the crotch of a pair of trousers, a supporting section positioned above and secured to said first section adapted to cover the front portion of said trousers leg intermediate the waistband and the crotch of said trousers, said body being provided with a cutaway extending from one end of said body substantially midway of the sides of said body and to and terminating in the adjacent one of the sides of said body substantially midway of the ends of said body and conforming to the crotch of a pair of trousers, the portion of the body contiguous to the cut-away forming said supporting section, a tie string positioned adjacent to the free end of the supporting section having a portion thereof intermediate its

10

15

ends secured to said free end of said supporting section, a strap having one end thereof secured to one side of said first section, a clasp secured to the other end of said strap, and a ring secured to the other side of said first section and adapted to be detachably engaged by said clasp for securing said first section to the leg of the user.
